UNITED STATES PATENT OFFICE.

HENRY A. WISE WOOD, OF NEW YORK, N. Y., ASSIGNOR TO THE WOOD NEWSPAPER MACHINERY CORPORATION, OF NEW YORK, N. Y., A CORPORATION OF VIRGINIA.

CASTING DEVICE FOR SEGMENTAL PLATES.

Application filed October 11, 1919, Serial No. 329,946. Renewed December 27, 1920.

This invention relates to that type of casting devices which involve a segmental back and semi-cylindrical core between which a stereotype printing plate is cast. More specifically it relates to that species of segmental plate casting machine in which the core is made double. So far as I am aware the double core has always been made in the form of a cylinder adapted to be turned over for alternate casts.

The principle object of this invention is to modify this double core in such a way as to permit of pouring at the side and providing a space for the sprue in contact with a surface of the core member. Further objects and advantages of the invention will appear hereinafter.

Reference is to be had to the accompanying drawings in which

20 Fig. 1 is an end elevation of a casting device made in accordance with this invention with the parts shown in full lines in position for casting and also showing them in open position in dotted lines;

25 Fig. 2 is a side view from the direction of the arrow 2 in Fig. 1;

Fig. 3 is a plan as indicated by the arrow 3 in Fig. 2;

30 Fig. 4 is a central longitudinal sectional view showing the plate in position between the core and back before they are separated;

Fig. 5 is a transverse sectional view showing the position of the parts when the back is withdrawn and the core remains in casting position;

35 Fig. 6 is a plan partly in section showing a modification; and

Fig. 7 is a central sectional view of the top of the same showing the core reversed and the end ring drawn back.

The invention is illustrated as mounted on the usual frame 9 which is naturally employed and it is shown as involving the usual segmental back 10 movable from the full line 45 to the dotted line position in Fig. 1, and back again by toggle 11 and operating arm 12. It is provided with the usual matrix clips 13 for holding the matrix 14, the construction and operation of these parts being so well known that no detailed description is necessary.

With this casting back I have provided a core member really consisting of three parts. These comprise two semi-cylindrical core elements 15 and a central part 16 for

rigidly connecting the two core elements 15 and spacing them apart. Each of the core elements has a semi-cylindrical casting area as shown more fully in Fig. 5 for forming the back of the cast plate A which is cast 60 against the matrix 14 when in place.

At the center of the whole structure is a shaft 17 on which is fixed a gear 18 operated by a gear 19 having an operating handle 20 for turning it. The core member can be 65 reversed by this means when the back 10 is drawn down.

The core casting areas are provided with small indentations 21 into which the metal flows so that the cast plate will be held on 70 the core member 15 as the latter is rotated. They are so weak however, that they can be easily broken by the simple operation of lifting the plate off the cylinder by hand.

The casting end rings 22 as shown in Fig. 75 4 are pushed up to position by springs 23 against the ends of the core and can be moved back by hand levers 24 to permit the turning of the core. In this way they do not move with the core but stay in the 80 back and the indentations 21, or some equivalent, are thus needed to hold the plate on the core as it turns over.

A modified form is shown in Figs. 6 and 7, in which the semi-circular end rings 25 85 turn with the core and plate. In this case springs 26 mounted on bolts 27 carried by the core yieldingly hold the end rings in position as the core turns over. There is a cam 28 on the frame at the top which engages in a notch 29 in the end ring and pulls it back as shown in Fig. 7 to release the plate after the core is turned over nearly to its final position. No indentations 21 are needed.

For the purpose of introducing metal into the mold cavity from the pouring-pot spout 31 I have provided a gate or hopper 32 pivotally mounted at 33 on a bracket 34 secured to the side of the back 10. This gate 100 can swing from the full to the dotted line position in Fig. 1. When in the full line position it forms with the side of the central part 16 of the core member, the sprue B of the casting as indicated in Fig. 5. 105 It will be seen therefore that the separation of the two semi-cylindrical cores is provided largely for the purpose of permitting of providing a space for this sprue so that the pouring can be done from the side.

I have shown also a saw 40 mounted on a slide 41 operated by a belt 42 passing over two pulleys 43 carried with the saw on the slide and two pulleys 44 mounted on stationary shafts. After the gate 32 is moved back to the dotted line position in Fig. 1 this slide is moved by operating the handle 45 and the saw cuts the sprue off the casting.

The operation has been practically described in referring to the elements of the drawings. The parts are located in the position shown in Fig. 1 for casting. When the cast is made and set the back is drawn down and the gate 32 is drawn back as shown by dotted lines in Fig. 1. Then the power is turned on and the saw moved across to cut off the sprue B. Then the handle 20 is turned and the double core reversed, although if the form shown in Fig. 20 4 is used the two levers 24 have to be operated first. The plate is simply lifted off, fracturing the projections at 21 and the device is ready for the parts 10 and 32 to be moved back to the position shown in full 25 lines in Fig. 1 against the core member for another casting.

This constitutes a very simple arrangement by which the plate can be cast from the side and is especially suitable for small 30 plants.

Although I have illustrated and described only a single form of the invention I am aware of the fact that modifications can be made therein by any person skilled in the art without departing from the scope of the invention as expressed in the claims. Therefore I do not wish to be limited to all the details of construction herein shown and described, but what I do claim is:—

40 1. The combination with a central member and a plurality of semi-cylindrical cores mounted rigidly on different sides thereof at a material distance apart, of a single semi-cylindrical back for casting printing plates adapted to co-operate with each of said cores, and means for moving said back radially toward and from the cores.

50 2. In a curved stereotype plate casting device, the combination with a curved back, of a double core comprising an element oblong in cross section having a rectangular central portion and two semi-cylindrical cores on opposite sides thereof for alternately co-operating with said back.

55 3. The combination with a semi-cylindrical printing plate casting back, and a longitudinal gate connected thereto for casting the sprue, of a core member having a plurality of cores for alternately entering the back, and means between the cores for constituting one wall of the sprue chamber.

60 4. The combination with a casting back and a reversible core member having two casting areas each adapted to cooperate with said back to form a casting chamber, of a

gate pivotally connected with the back and adapted to form a sprue chamber with one wall of the core member.

5. The combination with a printing plate casting back, and a reversible core member 70 comprising a non-casting portion and a plurality of semi-cylindrical casting areas located on different sides thereof, and a gate at the side of the casting chamber, said casting areas being spaced apart sufficiently to 75 provide a place between their side edges for receiving one side of the sprue.

6. A rotatable core member for use in casting segmental printing plates, said core member having two semi-cylindrical casting areas for two plates the axes of which are not in coincidence, said areas being provided with indentations for receiving metal and temporarily holding the cast plate in 80 position while being reversed.

7. The combination with a casting back and a reversible core, of a gate connected with the back and adapted to form a sprue chamber with one wall of the core member. 90

8. In a casting box for use in casting segmental printing plates, the combination of a reversible core provided with indentations for receiving metal and temporarily holding the cast plate in position while being reversed, with an end ring, and means for 95 drawing the end ring back longitudinally.

9. In a casting box for casting segmental printing plates, the combination with a reversible core, of an end ring, and means for automatically drawing the end ring back 100 longitudinally as the core nears its reversed position for delivery.

10. The combination with a back and a rotatable core for use in casting segmental printing plates, of an end ring, and means 105 in the back for drawing the end ring back longitudinally before the core is moved from the back.

11. A stereotype plate casting machine 110 for casting curved plates, including in combination a double cylindroid core adapted to produce plates with extra length columns, and a drag cooperating therewith.

12. A stereotype plate casting machine including in combination a rotatable cylindroid core having a short and a long diameter adapted to produce plates with extra length columns, and a drag co-operating therewith. 115

13. A stereotype plate casting machine including in combination an approximately cylindrically shaped rotatable casting core having a long and a short diameter and adapted to produce plates with extra length columns, and a reciprocable concave casting member co-operating with the core centrally with respect to the long diameter of the core. 120

14. A stereotype plate casting machine, 130 adapted to produce plates with extra length

columns, including in combination a core having a casting surface formed about an axis, the core extending at the sides past said axis, and a concave member forming therewith a casting chamber extending at the sides past the axis of said casting surface on the core.

15. A rotatable core for a stereotype plate casting machine, adapted to produce plates with extra length columns, having opposed cylindrical casting surfaces, each casting surface being formed about its own axis, the two axes being spaced apart slightly within the core, the axis of rotation of the core being between and in the common plane of the axes of the casting surfaces.

16. A stereotype plate casting machine, adapted to produce plates with extra length columns, including in combination a rotatable core having opposed cylindrical casting surfaces, each casting surface being formed about its own axis, the two axes being spaced apart slightly within the core, and a concave member co-operating to form a casting chamber extending symmetrically about the core with respect to and past the axis of the casting surface on the core.

17. A stereotype plate casting machine, adapted to produce plates with extra length columns, including in combination a cylindroid core and a drag co-operating therewith, and means for pouring in the hot metal at a straight edge of the casting chamber with the diameter across the plate substantially in horizontal position.

18. A stereotype plate casting machine, adapted to produce plates with extra length columns, including in combination an approximately cylindrically shaped rotatable casting core having a long and a short diameter, and a reciprocable concave casting member co-operating with the core centrally with respect to the long diameter of the core, and means for pouring in the hot metal at a straight edge of the casting chamber.

19. A stereotype plate casting machine, adapted to produce plates with extra length columns, including in combination a rotatable cylindroid core and a drag co-operating therewith, the core rotating about an axis

different from that of the casting surface of the core.

20. A curved stereotype plate casting cylindroid core, adapted to produce plates with extra length columns, and means for imparting a half rotation to the core, about an axis different from that of the casting surface of the core, between successive casting operations to bring the cast plate to delivery position.

21. A stereotype plate casting machine, adapted to produce plates with extra length columns, including in combination a rotatable core having a cylindrical casting surface formed about an axis, the core rotating about an axis behind said axis of the casting surface, a member having a circular surface engaging with a cast plate, to hold it to the core, said circular plate-engaging surface being concentric with the axis of rotation of the core.

22. A stereotype plate casting machine, adapted to produce plates with extra length columns, including in combination a rotatable core having a cylindrical casting surface formed about an axis, the core rotating about an axis behind said axis of the casting surface, a concave member co-operating to form a casting chamber, and an end plate for the casting chamber, having a semi-circular flange projecting into the casting chamber with its convex side concentric with the axis of the casting surface to hold down the matrix, and with its concave side concentric with the axis of rotation of the core, to hold the plate to the core as it is carried to delivery by the rotation of the core.

23. A stereotype plate casting machine including in combination a horizontally disposed core having two cylindrical casting surfaces formed about separate axes, the core having two longitudinally disposed approximately flat surfaces at the junctures of the two cylindrical surfaces, a co-operating concave casting member, and a pump nozzle discharging the hot metal at one of said flat surfaces of the core.

In testimony whereof I have hereunto affixed my signature.

HENRY A. WISE WOOD.
